(57) **CLAIM**

The ornamental design for a bottle, as shown and described.

DESCRIPTION

FIG. 1.1 is a left side view of a bottle;

FIG. 1.2 is a right side perspective view thereof;

FIG. 1.3 is a right side view thereof;

FIG. 1.4 is a front view thereof; and

FIG. 1.5 is a bottom view thereof.

The unshaded regions that are demarcated by broken lines show portions of the bottle that form no part of the claimed design. The dash-dot line is a boundary line that forms no part of the claimed design.
